F. W. O. KRETER.
FLUSHING DEVICE.
APPLICATION FILED MAY 27, 1914.

1,135,028.

Patented Apr. 13, 1915.

UNITED STATES PATENT OFFICE.

FRIEDRICH WILHELM OTTO KRETER, OF SAN ANTONIO, TEXAS.

FLUSHING DEVICE.

1,135,028.

Specification of Letters Patent. Patented Apr. 13, 1915.

Application filed May 27, 1914. Serial No. 841,259.

To all whom it may concern:

Be it known that I, FRIEDRICH WILHELM OTTO KRETER, a citizen of the United States, and a resident of San Antonio, in the county of Bexar and State of Texas, have invented 5 certain new and useful Improvements in Flushing Devices, of which the following is a specification.

My invention relates to flushing devices 10 for water-closets, and one of the main objects thereof is to provide a simple, positive, and comparatively inexpensive device which is readily applicable to any closet tank.

A further object is to provide means operable by the closet seat for setting the device, and resilient means for raising the valve when said seat resumes its normal position.

A further object is to provide such devices which are readily adjustable to meet 20 different conditions; and a further object is to make the operation of the device entirely automatic, therefore not requiring any action, or even attention, on the part of the user of the closet.

My invention is fully described in the following specification, of which the accompanying drawings form a part, in which the same parts are designated by the same reference characters in each of the views, and 30 in which:—

Figure 1 is a side elevation of a closet provided with my invention, partly in section; Fig. 2 is an enlarged, fragmentary, 35 view, partly in section, of details of the construction; Fig. 3 is a plan view of a seat lever which I employ; and Fig. 4 is a side view thereof.

In the drawings forming a part of this 40 application I have shown a water-closet *a* having a seat *a*² pivoted thereto, and provided with the tank *a*³ and water supply pipe *a*⁴, all of the usual or any desired construction, and a valve *a*⁵ normally closes the 45 upper end of the pipe *a*⁴.

My invention comprises a vertical tube *b* which is passed through a suitable opening in the bottom of the tank and held therein by means of lock-nuts *b*² and *b*³ in such manner as to make the connection proof against 50 leakage, as by washers, gaskets, or the like, and said tube is capped at its upper end, as shown at *b*⁴ and provided with a longitudinally arranged slot *b*⁵ just beneath said cap. 55 Secured to said tube, just below the slot *b*⁵, by means of a thumb-nut *c*, bolt, or equiva-

lent, is a band *c*² which has a horizontal arm thereon and which in turn carries a vertical bar, as shown at *c*³ and *c*⁴, respectively, and in the top of the said bar I pivot, as shown 60 at *c*⁵, a lever *c*⁶ having arms *c*⁷ and *c*⁸ of unequal lengths, the shorter being toward the tube *b* and the longer directed outwardly therefrom and provided, adjacent its end, with a plurality of holes for adjustably connecting a vertical rod *c*⁹ with said lever *c*⁶ and which is in turn connected, preferably 65 by means of a slip joint, with the valve *a*⁶.

Slidable vertically within the tube *b* is a rod *d* which carries a roller *d*² at its lower 70 end, in adjustable engagement therewith, and said rod carries an arm *d*³ at its upper end and which projects through the slot *b*⁵ and in which it is movable longitudinally of the tube, and I pivotally connect a dog to 75 the outer end of the arm *d*³, and which dog has a horizontal extension, in one position thereof, and a vertical extension, shown at *d*⁴ and *d*⁵, respectively, and the latter of which is hooked as shown and said dog is 80 arranged in the vertical plane of the lever *c*⁶ and with the inner end of which said hooked end *d*⁵ of the dog is adapted to engage, and I provide a coil spring *e* within 85 the tube *b*, normally forcing the rod *d*, and connected arm *d*³, downwardly.

Hinged to the closet seat *a*², as shown at *f*, is a lever *f*² upon the outer end of which the roller *d*² of the rod *d* bears, said lever having a shorter end *f*³ which normally rests 90 against said seat to prevent movement of said lever below the horizontal line of said seat and to move said seat on its hinge when the outer end of the lever *f*² is depressed, but said lever may be moved in the opposite direction, on its hinge, to permit the seat to be moved into a fully raised position to rest against the tank, and the coil spring *e*, through the rod *d*, normally holds the seat 95 in slightly raised position, as shown. When the seat is depressed by the weight of a person, the lever *f*² forces the rod *d* upwardly against the spring *e*, and the dog *d*⁴ is moved upwardly, the hooked upper end thereof striking the under surface of the lever arm *c*⁷ and, because of the curved formation of the said lever arm, and of the said hooked end of the dog, said dog is moved on its pivot whereby the hooked end passes beyond the lever arm *c*⁷ and, by reason of the fact that the horizontal extension 105 of said dog strikes against the under side of

the lever arm c^7 , said hooked end is again forced inwardly into engagement with said arm; when the closet seat is released from the weight which had been thereon, the 5 spring e forces the rod downwardly and thus moves the lever c^6 on its pivot, by means of the dog d^4 , into the alternate position shown in Fig. 2 whereby the valve a^5 is raised from its seat, and the water from 10 the tank is free to flush the closet bowl, the hooked end of the dog eventually slipping off the arm c^7 to permit the valve a^5 to resume its normal position.

The bracket c^8 is adjustable on the tube 15 b , and the roller d^2 is adjustable in the rod d , whereby the relationship of the dog d^4 and lever end c^7 may be acquired, and, while not so shown, I prefer to provide a lock-nut for 20 said roller d^2 at the lower end of the rod d , and various other changes in and modifications of the details shown and described 25 may be made, within the scope of the following claim, without departing from the spirit of my invention, or sacrificing its advantages.

My flushing device acts directly on the ball valve of the tank, and may be applied to any type of tank, and I may also, although not shown, connect my device with

a suitable valve mechanism for the water 30 supply for the tank, many forms of such water inlet means being at present in use, and to any of which my device may be adapted, if desired.

Having fully described my invention, what 35 I claim as new, and desire to secure by Letters Patent, is:—

The combination with a water-closet, of a hinged seat, a tank, a valve therein, a horizontal arm therein, a lever in pivotal connection with said arm, a vertically movable rod, a pivot on said rod, and a dog on said pivot having a hooked upper end for engagement with said lever, and a horizontal extension at the lower end of said dog arranged in the plane of said lever whereby 45 said dog is forced into vertical position, in its upper movement, by contact with said lever, to insure said hook engagement with said lever.

In testimony whereof I have signed my name to this specification in the presence of the subscribing witnesses.

FRIEDRICH WILHELM OTTO KRETER.
